GAME BOARD

Forrest E. Tyler, R.R. 3, Greensburg, Ind. 47240

Filed Apr. 8, 1971, Ser. No. 132,623

Term of patent 14 years

Int. Cl. D21—01

U.S. Cl. D34—5

FIG. 2

FIG. 1

FIG. 3

FIG. 4

FIG. 5

FIG. 1 is a top view of a game board showing my new design;

FIG. 2 is a top edge view of FIG. 1;

FIG. 3 is a right edge view of FIG. 1;

FIG. 4 is a bottom edge view of FIG. 1; and

FIG. 5 is a back view, to a reduced scale, of FIG. 1.

I claim:

The ornamental design for a game board, substantially as shown.
